UNITED STATES PATENT OFFICE.

WILLIAM W. WALKER, OF CAMDEN, NEW JERSEY, ASSIGNOR TO MACANDREWS & FORBES COMPANY, OF CAMDEN, NEW JERSEY, A CORPORATION OF NEW JERSEY.

MIXING-HEAD FOR FIRE-EXTINGUISHERS.

1,186,851.

Specification of Letters Patent. Patented June 6, 1916.

Application filed January 8, 1916. Serial No. 70,988.

To all whom it may concern:

It is known that I, WILLIAM W. WALKER, a citizen of the United States, residing at Camden, in the county of Camden and State of New Jersey, have invented new and useful Improvements in Mixing-Heads for Fire-Extinguishers, of which the following is a specification.

This invention relates to fire extinguishing apparatus and particularly to such apparatus when adapted to be used for extinguishing fires occurring on the surface of an inflammable liquid such as in an oil tank. Apparatus for this purpose usually includes means for storing near the oil tank, reservoirs containing substances which, when mixed together, will produce gas and foam, and the apparatus operates in such a way as to deposit this foam and gas which is noxious to combustion on the surface of the liquid in the tank. Such apparatus also should include a mixing head which is attached near the upper edge of the tank and provided with an outlet or spout for directing the foam onto the surface of the liquid.

A principal object of the present invention is to provide a mixing head for such an apparatus constructed so that it can be readily attached to the side wall of the tank, so that, in the event that the roof is blown off, the fire extinguishing apparatus will be left intact.

A further object of the invention is to construct the mixing head so as to prevent any possibility of the burning oil from the tank flowing down the mixing head.

A further object of the invention is to construct the mixing head so that there will be little danger of its being injured by the fire before it operates to deliver foam onto the surface of the oil, and further to provide a head operating so that the foam will be delivered onto the surface of the oil in considerable quantity, but at a relatively slow velocity, thereby disturbing as little as possible the surface of the burning oil. This effect is greatly conducive to the efficiency of this method of extinguishing fires.

The invention consists in the general construction, features, and details of the mixing head set forth in the following specification, while the broad scope of my invention is set forth in the appended claims.

In the drawing, Figure 1 is a vertical

section showing an embodiment of the invention and illustrating one manner in which it is applied to a tank. Fig. 2 is a front elevation of the mixing head representing the same detached from the tank and looking at the side of the mixing head which is disposed toward the tank. Fig. 3 is a plan of the mixing head.

In the embodiment of the invention illustrated, the head 5 comprises a receiver 6 which is located at the lower end of the head. This receiver is preferably in the form of an enlarged T connection, having oppositely disposed end walls 7 through which nipples 8 lead inwardly, said nipples connecting with delivery pipes 9 which conduct to the receiver any substances which will mix together to produce a gas and foam noxious to combustion, for example, these pipes may lead respectively from a reservoir containing a solution of bicarbonate of soda, and a reservoir containing aluminum sulfate in solution. The lower portion of the head 5 is formed into a substantially upright conducting leg 10, the lower end of which is preferably formed into a substantially cylindrical neck 11 to attach to the outlet 12 of the T connection 6. The mixing head is preferably formed of sheet metal or similar material bent or rolled to the proper form. The leg 10 is preferably formed of a substantially triangular forward wall 13 (see Fig. 2) and the rear wall 14 is preferably curved so that it is of substantially semi-circular form in horizontal cross section, but enlarging toward its upper end, at which point there is attached a substantially semi-circular bonnet 15 closed above by a cover plate 16 and provided on one side with a delivery spout 17 which projects substantially horizontally from the side wall of the bonnet 15. This spout 17 is of substantially rectangular cross section and has a downwardly inclined upper wall 18 which converges toward its bottom wall 19 in the direction of the tank 20, to which the head should be attached. In order to facilitate the attachment of this spout to the tank, I prefer to provide its under side with a flange 21 preferably forming part of an angle iron which extends transversely across the under side of the spout. This flange may be attached to the side wall of the tank below an opening 22 which is

formed in the side wall of the tank to receive the mixing head, and in order to additionally secure the spout in position, I prefer to extend the flange 21 around on the 5 vertical sides of the spout opening 23 (see Fig. 2), and I also prefer to provide the upper edge of the spout at its end with a substantially flat horizontal plate or bar 24, the ends of which extend beyond the spout 10 and form feet 25 for attachment to the under side of the flange 26 which is usually secured along the lip of the side wall of such a tank, and located under the edge of the cover 27 of the tank. If desired, the side plates 28 15 of the spout may be formed of plates having overlapping edges at 29 (see Fig. 1).

In order to prevent the oil in the tank from flowing down into the head 5 in case the level of the oil should rise above the 20 bottom of the spout, I prefer to provide a baffle wall or dam 30 which extends transversely across the spout adjacent where it is attached to the bonnet 15, and when the mixing head is foaming the foam passes 25 over the upper edge of this wall 30 and flows outwardly in the spout into the tank.

It is evident that by providing a spout on such a mixing head, and attaching it to the tank as suggested, the head itself is held 30 away from the tank and this is very desirable, because it tends to prevent injury occurring to the apparatus from the fire before the foam begins to be delivered over the oil. The outer end of the spout 17 is 35 preferably constructed so that it is relatively wide in a horizontal direction, and relatively narrow in a vertical direction, because this form operates to cause the spout to deliver the foam in a relatively wide thin 40 layer onto the surface of the oil, and the upwardly enlarging cross-section of the leg 10 of the head, operates to permit the foam to expand without creating pressure or any considerable velocity in the foam as it is 45 delivered from the spout.

As the mixing head is unattached to the cover of the tank, evidently if the cover should blow off in a fire, the mixing head will be left intact.

50 It is understood that the embodiment of the invention described herein is only one of the many embodiments my invention may take and I do not wish to be limited in the practice of the invention nor in my claims 55 to the particular embodiment set forth.

What I claim is:—

1. As a new article of manufacture, a mixing head to be used in connection with a tank for holding an inflammable liquid, having 60 a substantially upright conducting leg having means at its lower end for receiving substances which mix together to form a foam noxious to combustion, said mixing head having a cross-sectional area enlarging 65 toward its upper portion, and having a

laterally projecting spout with means adjacent the end of said spout for attaching the same to the side wall of the tank.

2. As a new article of manufacture, a mixing head to be used in connection with a 70 tank for holding an inflammable liquid, having a substantially upright conducting leg having means at its lower end for receiving substances which mix together to form a foam noxious to combustion, said mixing 75 head having a cross-sectional area enlarging toward its upper portion, and having a laterally projecting spout with means adjacent the end of said spout for attaching the same to the side wall of the tank, and a 80 baffle wall in said spout to prevent a flow of the liquid from the tank down said leg.

3. As a new article of manufacture, a mixing head to be used in connection with a tank for holding an inflammable liquid, having a substantially upright conducting leg, 85 having means at the lower end of said conducting leg for receiving substances which mix together to form a foam noxious to combustion, said means consisting of a T 90 having means for introducing the two substances into the T in opposite directions, said mixing head having a cross sectional area enlarging upwardly from said receiving means toward its upper portion and 95 having a laterally projecting spout to be attached to the side wall of the tank.

4. As a new article of manufacture, a mixing head to be used in connection with a tank for holding an inflammable liquid, having a substantially upright conducting leg, 100 said leg having means at its lower end for receiving substances which mix together to form a foam noxious to combustion, said head having a spout for delivering the foam 105 in a lateral direction at the side of the head, and a baffle wall in said spout for preventing the flow of the liquid from the tank down the leg.

5. As a new article of manufacture, a 110 mixing head to be used in connection with a tank for holding an inflammable liquid, having a substantially upright conducting leg, said leg having means at its lower end for receiving substances to mix together to form a 115 foam noxious to combustion, said head having a spout for delivering the foam in a lateral direction at the side of the head and means for preventing the flow of the liquid from the tank down said leg.

6. As a new article of manufacture, a mixing head to be used in connection with a tank for holding an inflammable liquid having a substantially upright conducting leg with a substantially flat forward wall to be 125 disposed adjacent to the tank and having a curved rear wall, said leg increasing in horizontal cross section in an upward direction, inlet means at the lower end of said leg to admit substances to mix together and form 130

a foam to rise and expand in said leg, a bonnet connected with the upper end of said leg and having a laterally projecting spout with means for attaching the same to the 5 side of the tank.

7. As a new article of manufacture, a mixing head to be used in connection with a tank for holding an inflammable liquid, said head having a horizontal cross section en- 10 larging from its lower end toward its upper end, said head having a laterally projecting

spout having means for attaching the same to the side wall of a tank and below the cover of the tank.

In testimony whereof I have hereunto 15 set my hand in presence of two subscribing witnesses.

WILLIAM W. WALKER.
